UNITED STATES PATENT OFFICE

EDWARD C. ANGELL, OF NEW YORK, N. Y.

APPARATUS FOR SEALING PAPER CONTAINERS

Application filed April 10, 1929. Serial No. 354,067.

This invention relates to apparatus for forming containers, especially those made of paper or similar material, that are substantially tubular or conical, with a bottom at one end, and when filled with a liquid, or other material, are sealed by pressing together or collapsing the opposite edges at the upper open end; and then a bent strip of metal, or other material, is sometimes applied to seal 10 the meeting edges and form a closure for the container.

This operation is sometimes carried out in a filling and sealing machine, in which the containers will intermittently advance, and 15 first travel below a filling mechanism or tank where they receive the contents and as the containers are advanced by the conveyer, they are collapsed, and at a further station in the machine are sealed.

20 These containers are sometimes constructed of a body in the form of a rolled blank in which the meeting edges are secured together, and form an upright seam in the container, and thus provide a kind of ledge on the outer 25 face of the body.

In the sealing machine the collapsing and sealing operations are sometimes produced by opposed jaws or clamping members, that are brought together against the container top 30 portion, and other jaws served to secure a sealing strip; and these two operations are sometimes effected in a vertical plane that is transverse to the plane of advance of the conveyers. Since the containers are usually provided with printed matter, it is an object to 35 collapse and seal the container so that the printed matter will appear on one of the comparatively flat sides or faces of the sealed container, and also the upright seam of the body 40 is preferably arranged on the opposite side of the sealed container from the said printed matter. Therefore it becomes necessary to so apply or position the containers on the conveyer, that when sealed the printed matter 45 and the seam will always have the same relative position to the said flat face, and it is an object of this invention to provide means for the proper positioning of the container on 50 the conveyers.

In the accompanying drawings showing one embodiment of my invention:

Fig. 1 is a plan view of the conveyer showing three of the seats for the containers.

Fig. 2 is a side elevation of the parts shown 55 in Fig. 1.

Fig. 3 is a plan view and Fig. 4 a front elevation of a portion of a filling and sealing machine.

Fig. 5 shows the containers on the chain 60 seat before sealing; and Fig. 6 shows the same after being collapsed.

As shown in the drawings the receptacles 6 are of conical form, comprising a body 7 and a bottom 8, in the form of a flanged disc with the margin of the body and disc rolled inwardly in the form of a bead. These containers are usually advanced on a conveyer, and in the form shown, the containers are carried on seat members 9, carried by an endless chain 10, that is intermittently advanced to bring the containers to a filling machine, and then to a collapsing member, and on further advance to a sealing member.

In Figs. 3 and 4, a machine of this kind is 75 indicated in which the chain 10 is carried by sprockets 11 and 12, whereby the containers on the seats 9 are brought to a filling machine, denoted generally by 13, then advanced to a collapsing machine 14, and on further 80 advance are engaged by the sealing mechanism 15. The collapsing is done by jaws 16 and 17 that are brought together on a vertical plane transverse to the path of the chain. The securing of the sealing strip is done by 85 similar pair of jaws 18 and 19, that are also brought together on a vertical plane transverse to the path of the conveyer, as shown in Figs. 3 and 4. The containers having the upright seam 5 of the body member, are placed 90 on the seats 9 so that this seam, will be in the medium line of the path on the conveyer, and preferably at the rear, in the direction of travel, as indicated by the arrow; it being understood that the printed matter on the container body is on the side opposite to this seam. Each of the seats 9 is provided with a stop member that will engage the edge of this seam when placed on the seat, and as 95 shown a bracket 20 is mounted on each seat, 100

with a stop arm 21 projecting therefrom. On the opposite side of each seat is mounted an arm 22 carried by a bracket 23, and this arm that may be resilient, will serve to press the container against the bracket 20 at the bead portion 8, while suitable stop pins 24, 25 on the seat at the rear, will properly position the container. The stop 21 and the arm 23 are preferably arranged to engage the body at the upper portion of the bead 8 and will tend to hold the container on the seat and prevent tipping thereof. It will be seen that the stop 21 will engage the seam 5 of the container when it is applied by sliding it from the side on to the seat until this seam is brought against the edge of the stop.

When the containers are applied, the operator will grasp them so that the seam 5 will be at the left hand side, and they are pushed into the seat between the bracket 20 and the arm 22, so that the seam 5 will engage the end of the arm 21, when the bottom bead on the container engages the stop pins 24, 25 at the rear, as indicated in Fig. 1. This will properly position the containers on the seats and when collapsed and sealed after filling, the seam will be in the middle of one flat edge at the top, and the printed matter on the opposite side. The arm 21, and also the arm 22 will engage the top of the bead of the bottom member and retain the containers on the seats.

What I claim is:—

1. In a machine for collapsing and sealing paper containers that have a side seam, the combination with the collapsing and sealing mechanism, and a carrier provided with a series of seat portions for the containers and which carrier is advanced to bring the containers on the seats to said collapsing and sealing mechanisms, of a stop guide arranged to engage the container side seam when placed on the carrier seat, whereby the side seam of the container will always lie in a certain predetermined fixed position relative to the line of seal on the container top as sealed by the machine.

2. In a machine for collapsing and sealing paper containers that have a side seam, the combination with the collapsing and sealing mechanisms, and a carrier provided with a series of seat portions for the containers and which carrier is advanced to bring the containers on the seats to said collapsing and sealing mechanisms, of a guide stop arranged to engage the container side seam when placed on the carrier seat, whereby the side seam of the container will always lie at the middle part of the line of seal on the container top as sealed by the machine.

3. In a machine for collapsing and sealing paper containers that have a side seam, the combination with the collapsing and sealing mechanisms and a carrier having a series of seats for the containers and which carrier is

advanced to bring the containers on the seats to the said collapsing and sealing mechanisms and which latter will effect a seal extending transverse to the path of travel of the carrier, of a stop guide arranged to engage the container side seam when placed on the carrier seat and which is located in the medium line of the carrier path of travel, whereby the side seal of the container will always lie at the middle part of the line of seal on the container top as sealed by the container.

4. In a machine for collapsing and sealing paper containers that have a side seam, the combination with the collapsing and sealing mechanisms and a carrier provided with a series of seats for the containers and which carrier is advanced to bring the containers on the seats to said collapsing and sealing mechanisms, of a stop guide on the carrier one for each said seat arranged to engage the container side seam when placed on the carrier seat, whereby the side seam of the container will always lie in a certain predetermined fixed position relative to the line of seal on the container top as sealed by the machine.

5. In a machine for collapsing and sealing paper containers that have a side seam, the combination with the collapsing and sealing mechanisms and a carrier provided with a series of seats for the containers and which carrier is advanced to bring the containers on the seats to said collapsing and sealing mechanism, of a guide stop arranged to engage the container side seam when placed on the carrier seat, whereby the side seam of the container will always lie at the middle part of the line of seal on the container top as sealed by the machine.

6. In a machine for collapsing and sealing paper containers that have a side seam, the combination with the collapsing and sealing mechanisms and a carrier having a series of seats for the containers and which carrier is advanced to bring the containers on the seats to the said collapsing and sealing mechanisms and which latter will effect a seal extending transverse to the path of travel of the carrier, of a stop guide on the carrier one for each said seat and arranged to engage the container side seam when placed on the carrier seat and which is located in the medium line of the carrier path of travel, whereby the side seal of the container will always lie at the middle part of the line of seal on the container top as sealed by the machine.

7. In a machine for collapsing and sealing paper containers that have a side seam a carrier provided with a series of seat portions for the containers and which carrier is advanced to bring the containers on the seats successively to said collapsing and sealing mechanisms, each carrier seat portion being provided with a bracket at one side on the base, the carrier having on the opposite side

an arm arranged to engage the container and press it against said bracket, a stop member on the seat portion at rear beyond said two opposite members adapted to engage the 5 container base when advanced between the said two members, and a stop guide carried by the bracket above base of the seat portion in position to have its end engage the side seam on the container, whereby the container 10 will always be seated in the same predetermined position relative to the line of seal on the container top as sealed by the machine.

8. In a machine for collapsing and sealing paper containers that have a side seam and 15 a bead extension at the base, a carrier provided with a series of seat portions for the containers and which carrier is advanced to bring the containers on the seats successively to said collapsing and sealing mechanisms, 20 each carrier seat portion being provided with a bracket at one side on the base, the carrier having on the opposite side an arm arranged to engage the container on the edge of the bead and press it against said bracket, a stop 25 member on the seat portion at rear beyond said two opposite members adapted to engage the container base when advanced between the said two members, and a stop guide carried by the bracket above base of the seat 30 portion in position to have its end engage the side seam on the container and also the bead, whereby the container will always be seated in the same predetermined position relative to the line of seal on the container top as 35 sealed by the machine.

Signed at New York city, N. Y., on March 16, 1927.

EDWARD C. ANGELL.
